UNITED STATES PATENT OFFICE.

JAMES DWYER, OF DETROIT, MICHIGAN.

DESIGN FOR A COOKING-STOVE.

SPECIFICATION forming part of Design No. 19,327, dated October 1, 1889.

Application filed August 10, 1889. Serial No. 320,415. Term of patent 7 years.

To all whom it may concern:

Be it known that I, JAMES DWYER, a citizen of the United States, residing at Detroit, county of Wayne, State of Michigan, have invented a certain new and useful Design for a Cook-Stove; and I declare the following to be a full, clear, and exact description of the same, such as will enable others skilled in the art to which it pertains to make and use the same, reference being had to the accompanying drawing, which forms a part of this specification.

The drawing is a side elevation and perspective of a stove illustrating my design.

15 The design embodies the following elements: the legs A, plain at the lower end and ornamented at their upper ends with a rosette with embossed scrolls about it.

B, C, and D are plain bands.

20 E is the oven-door, of swelled form, having its lower right-hand corner ornamented with spiral scrolls and with scroll-work extending across the bottom and up to the top of the door adjacent to the corner scroll. A spray of vines starts from near the hearth and embraces the oven-door handle and extends above the same, the remainder of the door being plain and smooth.

25 F is the fuel-door, of swelled form, plain with the exception of a horizontal scroll across the middle.

G is the warming-closet door, ornamented

essentially the same as the fuel-door and of swelled form.

H is a section beneath the reservoir, ornamented at the corner essentially the same as the oven-door E, and of swelled form. 35

What I claim is—

1. The design for a stove, consisting of legs A, with plain feet and ornamented at their 40 upper ends with rosettes surrounded by embossed scrolls, an oven-door E, and section H, of bulged form, having a plain surface ornamented at the lower corner with embossed scroll-work, and doors F G, of bulged form, 45 and with a plain surface ornamented by horizontal central scroll-work, substantially as shown.

2. In the design for a stove, the oven-door plain and of swelled form, ornamented at its 50 lower corner with embossed scrolls, and with a spray of vines or scrolls adjacent to the handle, substantially as shown.

3. In the design for a stove, the doors F G, of swelled form and plain surface, ornamented across the middle by horizontal scroll-work, 55 substantially as shown.

In testimony whereof I sign this specification in the presence of two witnesses.

JAMES DWYER.
